UNITED STATES PATENT OFFICE.

WILLIAM H. KENNEDY, OF CHICAGO, ILLINOIS, ASSIGNOR OF ONE-HALF TO LEWIS B. MILLER, OF CHICAGO, ILLINOIS.

RIVETING MACHINE.

Original application filed March 5, 1918, Serial No. 220,466. Divided and this application filed November 20, 1920. Serial No. 425,518.

To all whom it may concern:

Be it known that I, WILLIAM H. KENNEDY, a citizen of the United States, and a resident of the city of Chicago, county of Cook, and State of Illinois, have invented in certain new and useful Improvements in Riveting Machines, of which the following is a specification.

My invention relates to riveting machines of the type illustrated in my application filed March 5, 1918, Serial No. 220,466, of which this application is a division, and it has for its principal object the provision of a new and improved arrangement of parts by which the machine is automatically stopped at the end of a riveting operation and by which the machine is again thrown into operation through the use of a lever adjustably mounted in position.

Other objects will appear hereinafter.

The invention consists in the combinations and arrangements of parts hereinafter described and claimed.

The invention will be best understood by reference to the accompanying drawings forming a part of this specification, and in which,

Fig. 1 is a side view of my improved machine, partly broken away, and partly in section;

Fig. 2 is a central vertical section through a part of the machine shown in Fig. 1;

Fig. 3 is a horizontal sectional view showing the arrangement of the driving connections between the motor and the heavy gear by which an operative movement is given to the riveting jaws;

Fig. 4 is an enlarged detail view, being substantially a section taken on line 4-4 of Fig. 3; and

Fig. 5 is an end view of the parts shown in Fig. 3 as seen from the right in said figure.

Referring to the drawings, 10 indicates a frame of any suitable type having a fixed head or jaw 11 mounted thereon and a movable head or jaw 12 in alignment therewith adapted to be moved toward and from the jaw 11 for forming a head upon a rivet 50 interposed between the jaws. As is clearly shown in Fig. 1, the jaw 12 is adjustably mounted by means of screw threads in a slide-block 13 which is movably mounted

in a suitable slideway in the frame 10. The slide-block 13 is connected to a movably mounted block 14 by means of a pair of toggle levers 15 and 16, the lever 16 being provided with an extension arm 17 formed rigidly therewith. A lever 18 is pivotally mounted upon a pin 19 adjacent to the lever 16, the arm 17 being provided with a pin 20 extending laterally therefrom through a slot 21 formed in the lever 18. Another lever 22 pivotally mounted upon a pin 23 adjacent to the pin 19 is provided at its free end with a laterally extending pin 24 which also projects through the slot 21 of the lever 18, the pin 24 being provided with a roller 25 adapted to engage the edge of the arm 17. By the use of the mechanism described, when the lever 18 is given a stroke toward the left in Fig. 1, the lever 22 is also moved toward the left, serving to force the arm 17 likewise toward the left, the roller 25 being adapted to shift along the face of the arm 17 toward the knuckle of the toggle levers 15 and 16 for swinging such toggle levers into alignment. With the block 14 held in stationary position, the slide-block 13 will be moved downwardly by the operation as above described for effecting the desired riveting operation.

The means for operating the toggle levers 15 and 16 through the medium of the levers 18 and 22 comprises a second pair of toggle levers 30 and 31, the lever 30 being pivotally connected at its outer end to the lever 18, and the lever 31 being pivotally mounted upon the frame 10 by means of a pin 32. The pin 33 by which the toggle levers 30 and 31 are pivotally connected together is provided with an enlarged head adapted to slide in a dovetailed groove 34 formed in a lever 35 pivotally mounted upon the frame 10 by means of a pin 36. The lever 35 is connected by means of a link 37 with a rotary member 38 in the form of a gear, the construction being such that upon a rotation of the gear 38 in counter-clockwise direction in Fig. 1 the lever 35 is swung back and forth toward and from the left side of the machine as shown in said Fig. 1. As will be readily understood, upon the movement of the lever 35 toward the left in said figure, the pin 33 is caused to move along the slot 34 toward the axis of the lever 35,

serving to move the lever 18 toward the left for effecting an operative movement of the movable jaw 12. As is fully set forth in my prior application above referred to, 5 the proportions of the parts are such that the toggle levers 30 and 31 are brought into alignment with each other at or before the time when the lever 35 reaches the limit of its movement toward the left as above described, whereby the full toggle effect is 10 obtained. A pin 39 is provided upon the lever 35 for moving the toggle levers out of their aligned locking position as the lever 35 swings toward the right.

15 The means for rotating the gear 38 comprises a motor 40 provided with a driving pinion 41 upon the motor shaft 42. Meshing with the pinion 41 is a gear 43 which is revolubly mounted upon a sleeve 44 which 20 in turn is revolubly mounted in a sleeve 45 fixed upon the frame 10. As is shown in Fig. 3, the gear 43 is hollowed out in the form of a friction clutch member. A co-operating friction clutch member 46 is feathered upon the sleeve 44 so as to rotate therewith but to be free to slide longitudinally thereof. A spring 47 is interposed between the clutch member 46 and the end of the sleeve 44 serving normally to hold the clutch members 25 30 out of engagement with each other. A rod 48 is mounted loosely in the sleeve 44, being connected at one end with the clutch member 46 in such manner that movement of the rod 48 toward the right in Fig. 3 35 serves to throw the clutch members into operative engagement with each other against the action of the spring 47. As will be readily understood, with the clutch members out of operation, the gear 43 is adapted 40 to run freely with respect to the sleeve 44. When, however, the clutch members are thrown into operative engagement, the sleeve 44 is caused to rotate with the gear 43. A pinion 49 fixed upon the sleeve 44 meshes 45 with the gear 38, whereby the motor 40 is adapted to drive said gear for effecting a riveting operation as above described.

Means is provided for moving the rod 48 toward the right in Fig. 3 for effecting 50 an operative engagement of the clutch members. This means, in the construction shown, comprises a sleeve 50 fixedly mounted upon the rod 48, said sleeve being provided with a cam 51 in the form of a screw- 55 thread adapted to co-operate with an internal screw-thread formed on the inner face of a bushing 52 carried by the frame 10. By the use of cam means of this type, upon 60 a rotary motion of the rod 48, said rod is moved longitudinally with respect to the sleeve 44 for moving the clutch members into or out of operative engagement. The pitch of the thread 51 is such that when 65 the rod 48 is moved toward the right in Fig. 3 against the action of the spring 47,

the rod is automatically locked by friction against rotary motion in the reverse direction. The means for rotating the sleeve 50 and rod 48 for effecting the operative engagement of the clutch members 46 and 43 70 comprises a plate 53 fixed upon the sleeve 50 and the rod 48 by means of a pin 54 as is best shown in Fig. 3. Revolubly mounted upon the sleeve 50 adjacent to the plate 53 is an arm or lever 55 which is provided with 75 a socketed lug 56 within which is slidably mounted a pin 57, a coiled spring 58 being interposed between the pin 57 and the outer end of the lug for holding the pin yielding 80 at the limit of its motion toward the right in Figs. 3 and 4. As is best shown in Fig. 4, the pin 57 is adapted to extend into one of a series of openings 59 through the plate 53 for causing the plate to rotate with the arm or lever when such arm is 85 moved in clock-wise direction in Fig. 5. As is best shown in Fig. 4 the outer end of the pin 57 is beveled so as to permit motion of the arm 55 in counterclock-wise direction in Fig. 5 without causing a corresponding motion of the sleeve 50 and the rod 48. By the use of this construction, the arm or lever 55 is adapted to be used for turning the sleeve 50 and the rod 48 for effecting engagement of the clutch members, 90 the arm 55 being free to turn in counterclock-wise direction in Fig. 5, either before or after an effective stroke of the arm, for being brought to the desired position upon the frame, this movement in counterclock-wise direction in said Fig. 5 being effected 100 without any change in position of the sleeve 50.

Means is provided for giving the sleeve 50 and the rod 48 a rotary movement in reverse direction as compared with that effected by the arm 55 for throwing the clutch members 43 and 46 out of engagement, such means being adapted to act automatically at the end of a complete rotation of the gear 38. This means comprises a pinion 60 fixed upon the end of the sleeve 50 adjacent to the pinion 49. Mounted upon the gear 38 so as to be brought into engagement with the pinion 60 there is a segmental gear 61, as is 115 best shown in Fig. 2. The segmental gear 61 is mounted in position by means of bolts 62 extending through a circumferential slot 63 formed in the gear 38, the arrangement being such as to provide for an adjustment of 120 the segmental gear 61 with respect to the gear 38.

As will be readily understood, when it is desired to effect a riveting operation, the arm or lever 55 is given a stroke in clock-wise direction in Fig. 5 for turning the sleeve 50 and effecting a longitudinal movement of the rod 48, serving to bring the clutch members into engagement, the cam or thread 51 acting automatically to hold the clutch 130

- members in continued engagement after the arm 55 has been released. When the gear 38 has been given a complete rotation for a single complete riveting operation, the 5 segmental gear 61 comes into contact with the pinion 60 serving to rotate the pinion 60 in counterclock-wise direction in Fig. 2 for rotating the sleeve 50 and throwing the clutch members out of engagement.
- 10 While I have illustrated and described the preferred form of construction for carrying my invention into effect, this is capable of variation and modification without departing from the spirit of the invention. I, 15 therefore, do not wish to be limited to the precise details of the construction set forth, but desire to avail myself of such variations and modifications as come within the scope of the appended claims.
- 20 Having described my invention, what I claim as new and desire to secure by Letters Patent is:—
1. A machine of the class described comprising relatively stationary and movable 25 jaws; a driving element; an operative connection between said driving element and said movable jaw; means for automatically disconnecting said driving element upon each cycle of operation of the machine, said 30 means comprising a clutch and a rotatable cam member to shift said clutch; and means on one of the parts driven by said driving element for automatically rotating said cam member for shifting said clutch upon each 35 cycle of operation of the machine, substantially as described.
2. A machine of the class described comprising relatively stationary and movable jaws; a driving element; an operative 40 connection between said driving element and said movable jaw; means for automatically disconnecting said driving element upon each cycle of operation of the machine, said means comprising a laterally movable mem- 45 ber and clutch; a pinion mounted on said member and adapted, when rotated, to move said member and clutch laterally; and means on one of the parts driven by said driving element adapted to engage with and rotate 50 said pinion once during each cycle of operation of the machine, substantially as described.
3. A machine of the class described, comprising relatively stationary and movable 55 jaws; a driving element; a clutch for operatively connecting said driving element with said movable jaw; a rotary member adapted by rotation in one direction to throw the clutch into operation and adapted automatically to hold the clutch against movement 60 out of operative position; and means adapted at the end of a riveting operation to rotate said rotary member in reverse direction for disconnecting said clutch; substantially as 65 described.
4. A machine of the class described, comprising relatively stationary and movable jaws; a driving element; a clutch for operatively connecting said driving element with said movable jaw; a rotary member connected with the movable member of said clutch; a cam adapted upon the rotation of said rotary member in one direction to move said member longitudinally for throwing the clutch into operation and for locking the 70 clutch against movement out of operative position; and means adapted at the end of a riveting operation to rotate said rotary member in reverse direction for disconnecting said clutch; substantially as described. 75
5. A machine of the class described, comprising relatively stationary and movable jaws; a gear operatively connected with said movable jaw for moving it toward the stationary jaw; a driving element; a clutch for 80 operatively connecting said driving element with said gear; a rotary member connected with the movable member of said clutch; a cam adapted upon the rotation of said rotary member in one direction to move said 85 rotary member longitudinally for throwing the clutch into operation; and means adapted at the end of a complete rotation of said gear to rotate said rotary member in reverse direction for disconnecting said clutch; substantially as described. 90
6. A machine of the class described, comprising relatively stationary and movable jaws; a gear operatively connected with said movable jaw for moving it toward the stationary jaw; a driving element; a clutch for 95 operatively connecting said driving element with said gear; a rotary member connected with the movable member of said clutch; a cam adapted upon the rotation of said rotary member in one direction to move said rotary member longitudinally for throwing the clutch into operation; and means adapted at the end of a complete rotation of said gear to rotate said rotary member in reverse direction for disconnecting said clutch; substantially as described. 100
7. A machine of the class described, comprising relatively stationary and movable jaws; a gear operatively connected with said movable jaw for moving it toward the stationary jaw; a driving element; a clutch for 105 operatively connecting said driving element with said gear; a rotary member connected with the movable member of said clutch; a cam adapted upon the rotation of said rotary member in one direction to move said rotary member longitudinally for throwing the clutch into operation; a pinion mounted on said rotary member; and a segmental gear carried by said first named gear adapted at 110 the end of a complete rotation of said first named gear to rotate said rotary member by engagement with said pinion for disconnecting said clutch; substantially as described. 115
8. A machine of the class described, comprising relatively stationary and movable jaws; a gear operatively connected with said movable jaw for moving it toward the stationary jaw; a driving element; a clutch for 120 operatively connecting said driving element with said gear; a rotary member connected with the movable member of said clutch; a cam adapted upon the rotation of said rotary member in one direction to move said rotary member longitudinally for throwing the clutch into operation; a pinion mounted on said rotary member; and a segmental gear adjustable circumferentially on said first named gear adapted at the end of a complete rotation of said first named gear 125

to rotate said rotary member by engagement with said pinion for disconnecting said clutch; substantially as described.

8. A machine of the class described, comprising relatively stationary and movable jaws; a driving element; a clutch for operatively connecting said driving element with said movable jaw; a rotary member connected with the movable member of said clutch; 10 screw-thread means adapted upon the rotation of said rotary member in one direction to move said rotary member longitudinally for throwing the clutch into operation and for locking the clutch against movement out 15 of operative position; and means adapted at the end of a riveting operation to rotate said rotary member in reverse direction for disconnecting said clutch; substantially as described.
- 20 9. A machine of the class described, comprising a frame; a sleeve revolvably mounted on said frame; a clutch member revolvably mounted on said sleeve; means for driving said clutch member, a second clutch member feathered on said sleeve adapted to be moved into operative engagement with said first named clutch member for connecting it with said sleeve; a rod revolvably mounted in said sleeve and connected with said sec- 25 ond clutch member adapted by longitudinal movement with respect to said sleeve to throw said clutch into operation; riveting mechanism carried by said frame; a rotary member by a complete rotation of which said riveting mechanism is moved through a cycle of 30 operation; operative connections between said gear and said sleeve for driving said gear; means for giving said rod a rotary movement; means adapted upon rotation of 35 said rod in one direction to move the rod longitudinally for throwing the clutch members into operative engagement; and means adapted at the end of a complete rotation of 40 said gear to rotate said rod in reverse direction for throwing said clutch members out of operative engagement; substantially as described.

10. A machine of the class described, comprising a frame; a sleeve revolvably mounted 50 on said frame; a clutch member revolvably mounted on said sleeve; means for driving said clutch member; a second clutch member feathered on said sleeve adapted to be moved into operative engagement with said first named clutch member for connecting it with said sleeve; a rod revolvably mounted in said sleeve and connected with said sec- 55 ond clutch member adapted by longitudinal movement with respect to said sleeve to throw said clutch into operation; riveting mechanism carried by said frame; a rotary member by a complete rotation of which said riveting mechanism is moved through a cycle of 60 operation; operative connections between said gear and said sleeve for driving said

gear; means for giving said rod a rotary movement; cam means adapted upon rotation of said rod in one direction to move the rod longitudinally for throwing the clutch members into operative engagement and 70 adapted automatically to hold said clutch members against movement out of operative engagement; a pinion mounted on said rod; and a segmental gear carried by said first named gear adapted at the end of a complete 75 rotation of said first named gear to rotate said rod in reverse direction by engagement with said pinion for throwing said clutch members out of operative engagement; sub- 80 substantially as described.

11. A machine of the class described, comprising a frame; a sleeve revolvably mounted on said frame; a clutch member revolvably mounted on said sleeve; means for driving said clutch member, a second clutch member feathered on said sleeve adapted to be moved into operative engagement with said first named clutch member for connecting it with said sleeve; a rod revolvably mounted in said sleeve and connected with said second clutch member adapted by longitudinal movement with respect to said sleeve to throw said clutch into operation; riveting mechanism carried by said frame; a rotary member by a complete rotation of which said riveting 95 mechanism is moved through a cycle of operation; operative connections between said gear and said sleeve for driving said gear; means for giving said rod a rotary movement; a second sleeve fixedly mounted on 100 said rod; a screw thread on said second sleeve; screw thread means engaging said first named screw-thread adapted upon rotation of the rod in one direction to move the rod longitudinally for throwing the clutch members into operative engagement and 105 adapted automatically to hold the clutch members against movement out of operative engagement; and means adapted at the end of a complete rotation of said gear to rotate said second sleeve and said rod in reverse direction for throwing said clutch members out of operative engagement; sub- 110 substantially as described.

12. A machine of the class described comprising relatively stationary and movable jaws; a driving element; means for operatively connecting said driving element and said movable jaw; means for making and breaking the connection between said driving element and said jaw comprising a rotatively adjustable handle; and connecting means co-operating with said handle whereby the latter is operable when rotated in one direction and disconnected and free when rotated in the opposite direction; substantially as described.

13. A machine of the class described comprising relatively stationary and movable jaws; a driving element; means for opera- 130

tively connecting said driving element and in the opposite direction; substantially as 10
said movable jaw; means for making and described.
breaking the connection between said driv-
ing element and said movable jaw, com-
5 prising a rotatively adjustable handle;
and a spring pressed beveled pawl co-
operating with said handle whereby the lat-
ter is operable when rotated in one direc-
tion and disconnected and free when rotated

In testimony whereof I have signed my
name to this specification in the presence of
two subscribing witnesses.
